UNITED STATES PATENT OFFICE.

ROBERT T. SUDDENDORF, OF CINCINNATI, OHIO, ASSIGNOR TO THE WITT CORNICE COMPANY, OF CINCINNATI, OHIO.

CAN STRUCTURE.

Application filed February 9, 1923. Serial No. 618,135.

To all whom it may concern:

Be it known that I, ROBERT T. SUDDENDORF, a citizen of the United States, and a resident of Cincinnati, in the county of 5 Hamilton and State of Ohio, have invented certain new and useful Improvements in Can Structures; and I do hereby declare the following to be a full, clear, and exact description of the invention, such as will enable others skilled in the art to which it 10 appertains to make and use the same.

This invention relates to improvements in can structures and more particularly to means for connecting casters thereto,—one 15 object of the invention being to provide simple, substantial and efficient supporting devices for connecting casters with a can or receptacle in a manner to guard against accidental disconnection of such supporting 20 devices and the casters from the can or becoming loose.

With this and other objects in view, the invention consists in certain novel features of construction as hereinafter set forth and 25 pointed out in the claim.

In the accompanying drawings,—

Figure 1 is a view illustrating the application 30 of my improvement to a receptacle such as commonly used for receiving ashes or garbage.

Figure 2 is a view in section of a portion 35 of a can with my improvements applied thereto.

Figure 3 is a view in elevation of the supporting bracket.

Figure 4 is a plan view of the same, and Figure 5 is a face view of said bracket.

A can or receptacle is indicated at 1 and provided at its bottom with a band which 40 forms a flange 2 depending from the bottom 3 of the can or receptacle.

The can is supported upon a plurality of casters 4 (four such casters being shown in the drawings) and each caster is connected 45 with the flange 2 of the can through the medium of a supporting bracket 5. As all of the supporting brackets 5 are the same in construction, a specific description of one will suffice.

Each supporting bracket 5 comprises a 50 slightly curved plate or casting 6 having at its intermediate portion an enlargement 7 in which a socket 8 is formed to receive the spindle 9 of a caster structure 10. The plate or casting 6 is provided at respective 55 sides of the intermediate enlargement 7 with holes 11 for the passage of rivets 12 which secure the device to the flange 2 of the can. The bracket 5 may be recessed as at 13 so that the portions of the plate 6 at respective 60 sides of the enlargement 7 only bear directly against the inner face of the can flange 2. At its lower edge the plate or casting 6 of the bracket 5 is provided with a lateral 65 flange 14 which, when the device is secured in place on the can flange, will be disposed to engage the lower edge of said can flange and this will result in avoiding shearing of the rivets when weighty material is placed in the can.

By referring particularly to Fig. 2, it will be noted that the bottom edge of the can abuts the top edge of the bracket so that the strain imposed upon the caster is transmitted directly thereto through the bracket 70 in such a manner that the rivets connecting the bracket to the flange or band of the can do not have to carry any weight and are called upon merely to retain the bracket in place. Moreover, the bracket has an ex- 75 tended bearing against the flange and the bottom edge of the can so that any possible tendency of the spindle and bracket to rock is effectually overcome.

Slight changes might be made in the details of construction of my improvements without departing from the spirit of my invention and hence I do not wish to be restricted to the precise details herein set forth.

Having fully described my invention what I claim as new and desire to secure by Letters-Patent, is:

The combination with a can having a flange depending below its bottom edge, of 95 a bracket fitting against the inner side of said flange, the top of the bracket abutting the bottom edge of the can and the bracket

being provided at its bottom with an outwardly projecting lip engaging under the lower edge of the flange, securing devices inserted through the flange and the end portions of the bracket, and a caster carried by the bracket.

In testimony whereof, I have signed this

specification in the presence of two subscribing witnesses.

ROBERT T. SUDDENDORF.
